Schmidt & Howlett LLP(57) **CLAIM**

We claim, the ornamental design for center console television stand, as shown and described herein.

DESCRIPTION

FIG. 1 is a front, right perspective view of a center console television stand in accordance with our invention;

FIG. 2 is a right-side view thereof, the left side being a mirror image;

FIG. 3 is a front elevation view thereof;

FIG. 4 is a rear elevation view thereof;

FIG. 5 is a plan view thereof; and,

FIG. 6 is a bottom view thereof.

The portions of the drawings shown in broken line format are representative of structure or environment in which the invention may be found, and form no part of the claimed invention.
